UNITED STATES PATENT OFFICE.

PAUL BALZE, OF LEONIA, NEW JERSEY.

TANK-SIPHON.

1,090,189.

Specification of Letters Patent. Patented Mar. 17, 1914.

Application filed April 4, 1913. Serial No. 758,811.

To all whom it may concern:

Be it known that I, PAUL BALZE, a citizen of the United States, and a resident of Leonia, in the county of Bergen and State 5 of New Jersey, have invented a new and Improved Tank-Siphon, of which the following is a full, clear, and exact description.

This invention relates to water distribution, and has particular reference to siphons 10 for periodically delivering fluids, especially water, from tanks.

Among the objects of this invention is to provide a siphon adapted especially for flush tanks, the nature of the siphon being 15 such that it is valveless and hence precludes any possibility of leakage.

A further object of this invention is to improve flush tank siphons so as to render them both easier and surer of operation than 20 is usually true of such devices, the arrangement being such that there is no possibility for any movable part of the device to fail to operate, and also to insure that the siphonic action will be positively initiated 25 as a result of a minimum amount of water caused to be passed through the siphon.

The foregoing and other objects of this invention will hereinafter be more fully described and claimed and illustrated in the 30 drawings forming a part of this specification in which like characters of reference indicate corresponding parts in all the views, and in which—

Figure 1 is a plan view of my improvement applied to a flush tank, the cover being removed; Fig. 2 is a vertical sectional view on the line 2—2 of Fig. 1; Fig. 3 is a bottom plan view of the siphon; Fig. 4 is a transverse section of the same on the line 40 4—4 of Fig. 2, and Fig. 5 is a detail in section of the dome taken at right angles to Fig. 2.

The several parts of the device may be made of any suitable materials, and the relative sizes and proportions of the same as 45 well as the general design of the equipment may be varied to a considerable extent without departing from the spirit of the invention hereinafter more definitely described 50 and specifically claimed.

I show at 10 a diagrammatic representation of any suitable tank which is designed to hold a certain body of water 11 and from 55 which tank the water is to be delivered, when desired, by my improved mechanism. No special means are shown for supplying

the tank with water inasmuch as the same constitutes no part of this invention. This device will be understood as being adapted especially for closet flush tanks of either the 60 low-down or high types, but is useful also in other relations.

At 12 I show the principal part of my siphon mechanism, the same comprising a siphon 13 and a chamber 14 integral therewith. As shown in the drawings, the siphon comprises a short leg 15 and a long leg 16 separated by a wall 17 which is shown as integral with the other part of the siphon and extends upwardly from the base 18. The 70 two legs of the siphon are connected by a hemispherical dome 19. The wall 17 is flat and straight and its upper edge is horizontal and constitutes a diameter of said hemispherical dome 19. No matter, therefore, 75 how little water passes through the siphon initially, it will flow over said edge in a sheet as wide as the wall 17.

The chamber 14 is substantially sector shaped and is of any suitable width, shown 80 substantially as wide as the main portion of the siphon. The bottom of the chamber 14 is open except as stated below, and is provided with a recess 20 at its lower outer edge. It will be noted, therefore, that the 85 bottom of the chamber is spaced, as shown at 21, from the bottom of the tank. The upper portion of the chamber communicates directly with the lower end of the short leg 15. A vane 22 is pivoted at 23 at the center 90 of curvature of the chamber and is movable freely within the same through an angle of substantially 90 degrees. The vane normally lies opposite or within the open bottom of the chamber and with its free end 95 below the recess 20 above referred to.

As shown especially in Fig. 4, the main siphon is preferably of a cylindrical form, the same being divided into two substantially equal semi-circles in cross section by the 100 wall 17. The lower end of the long leg merges, however, into a cylindrical spud 24, through which the siphon mechanism is connected to and extends through the bottom of the tank 10. The relative sizes of the spud 105 and the siphon legs may vary to a certain extent in practice, but I prefer to construct the same so as to preserve a ratio between the diameters of the spud and the combined siphon legs of substantially 2 to 3. The 110 cross sectional area, therefore, of the spud will be approximately equal to the cross sec-

tional area of either leg or perhaps a little less. As shown especially in Fig. 2, the spud is offset outwardly from the wall or center of the siphon structure whereby I provide a substantially flat shelf or ledge 25 at the base of the wall 17. It will be apparent, therefore, that the minimum amount of water flowing over the horizontal top of the wall 17 will flow down and strike against 5 said ledge 25 and splash outwardly across the top of the spud and radially of its axis and thereby cause the starting of the siphonic action because of the exclusion of air tending under such circumstances to rise 10 within the longer leg. The central portion 25' of said ledge may be comparatively narrow, but because of the flared portions at 25" where said ledge merges into the spud proper, the water flowing down along the 15 edges of the wall will be caused to dash or splash diagonally toward the axis of the spud as indicated by the arrows on Fig. 4, insuring the prompt and certain action of the siphon starter with a minimum quantity 20 of water flowing initially over the wall.

Any suitable mechanism may be used to swing the vane around its pivot 23 and cause a portion of the water normally within the chamber to be lifted or pushed over the top 25 of the wall 17. As shown herein by way of illustration of any such suitable mechanism, I provide an arm 26 connected to the pivot 23, and a rod 27 is pivotally connected at its ends to said arm and a crank 28 mounted 30 upon a rock shaft 29. Said shaft is shown journaled in the walls of the tank and may be operated by a pendent handle 30 as is customary in low-down flush tanks. When the handle 30 is swung in either direction, 35 the vane will be caused through the connections indicated to be swung upwardly, and though the vane is loosely fitted within the chamber 14, a sufficient quantity of water will be lifted and caused to flow over the top 40 of the wall 17 to insure initiation of the siphonic action. When the water is thus caused to flow through the siphon, the flow will lift the vane substantially against the wall 17 if the action of the operator is not 45 sufficient to do so, allowing free outflow of the water into and through the chamber. As soon as the flow of water through the siphon ceases, the vane will be restored automatically 50 to its normal position, allowing the water entering the tank to find its intended level within the chamber and short leg, the same entering the chamber through the open bottom and the recess 20. By providing a loose fit between the edges of the vane and 55 the inner walls of the chamber, the device may be made much cheaper and operated much more reliably than if an attempt be made to provide a close fit.

Flush tanks as usually made and operated 60 are so arranged that after the siphon is once

started, practically all of the water will be drawn from the tank, occasioning in many cases an unnecessary use of water with the accompanying expense in such localities where water is paid for according to the 70 number of cubic feet consumed. In order, therefore, to variably determine the amount of water to be delivered from the tank in a simple and reliable manner, I employ a tube 75 31 open at its lower end and connected at its upper end with the interior of the dome. Said upper end is connected in any convenient manner, as shown at 32, passing through the wall of said dome. Said tube is preferably made of flexible material such as 80 lead or other suitable metal. As soon as the level of the water within the tank is reduced to the lower end of the pipe 31, air will be admitted upwardly through the same into the dome 19, breaking the siphon. By 85 bending upwardly the lower end of said pipe the amount of water to be delivered will be reduced inasmuch as the amount to be delivered according to any adjustment of the pipe will be represented by the vertical distance 90 between the normal surface of the water and the level of said lower end of the pipe. The excess of water within the tank, therefore, will simply be retained and serve to constitute a part of the water again filling 95 the tank.

Having thus described my invention, I claim as new and desire to secure by Letters Patent:

1. In a device of the character set forth, 100 the combination with a tank, of siphon mechanism therefor comprising a valveless siphon and connected chamber, the siphon and chamber being of substantially the same width, the lower end of the longer leg of the 105 siphon merging into a spud fitted in and extending through the bottom of the tank, said longer leg where it merges into the spud on the side thereof adjacent the shorter leg providing a substantially horizontal ledge, said 110 legs being separated by a flat wall having a straight horizontal upper edge and means movable within the chamber to cause a portion of water to be delivered through the siphon and caused to flow in a sheet over 115 said horizontal edge and splash upon said ledge and thence across the center of the spud.

2. In a tank siphon, the combination of 120 a cylindrical structure comprising longer and shorter legs connected at their upper ends by a hemispherical dome and separated by a straight flat square-topped vertical wall, each of said legs in cross section being substantially semi-circular, a cylindrical spud formed at the lower end of the longer leg and having its axis offset outwardly from said wall, there being provided at the bottom of the longer leg between the spud and the wall a flat horizontal ledge, a chamber 125

constituting an extension of said shorter leg and having an open bottom and a recess at its outer edge, and means movable within the chamber to cause a portion of water to be forced through the shorter leg and initially in a sheet over the top of said wall whence it falls upon said ledge and splashes radially toward the axis of the spud, said movable means lying normally below said re-

cess and operating out of contact with the inner walls of the chamber.

In testimony whereof I have signed my name to this specification in the presence of two subscribing witnesses.

PAUL BALZE.
